(57) **CLAIM**

The ornamental design for a flashlight, as shown and described.

DESCRIPTION

FIG. 1 shows a perspective view of a flashlight according to the present invention.

FIG. 2 shows a front view of the flashlight of FIG. 1.

FIG. 3 shows a right side view of the flashlight of FIG. 1, the left side view being a mirror image of the right side view.

FIG. 4 shows a rear view of the flashlight of FIG. 1.

FIG. 5 shows a top view of the flashlight of FIG. 1; and,

FIG. 6 shows a bottom view of the flashlight of FIG. 1.

The broken lines are for illustrative purposes only, and form no part of the claimed design.

1 Claim, 3 Drawing Sheets

FIG.3

FIG.4

FIG. 5

FIG. 6
